United States Patent

Des. 241,586
Patented Sept. 28, 1976

241,586

SOLE

Ladislav Sebestik, Lorraine, Quebec, Canada, assignor to
Baron Rubber Ltd., St. Jerome, Quebec, Canada

Filed Jan. 30, 1976, Ser. No. 653,821

Claims priority, application France Nov. 6, 1975

Term of patent 14 years

Int. Cl. D2—04

U.S. Cl. D2—320

FIG. 1 is a top plan view of a sole showing my new design;

FIG. 2 is a side elevational view thereof, the other side being substantially identical; and

FIG. 3 is a bottom plan view thereof.

I claim:

The ornamental design for a sole, substantially as shown.
